(57) **CLAIM**

The ornamental design for a cable harness with protective casing, as shown and described.

DESCRIPTION

FIG. 1 is a front perspective view of a cable harness with protective casing showing our new design;

FIG. 2 is a right side view thereof;

FIG. 3 is a left side view thereof;

FIG. 4 is a front view thereof;

FIG. 5 is a rear view thereof;

FIG. 6 is a bottom view thereof;

FIG. 7 is a top view thereof;

FIG. 8 is an enlarged front perspective view of the cable harness with protective casing shown in FIGS. 1-8 with unclaimed environment removed for clarity;

FIG. 9 is a right side view thereof;

FIG. 10 is a left side view thereof;

FIG. 11 is a front view thereof;

FIG. 12 is a rear view thereof;

FIG. 13 is a bottom view thereof; and,

FIG. 14 is a top view thereof.

The broken lines depicting the remainder of the cable harness with protective casing show features that form no part of the claimed design.

1 Claim, 14 Drawing Sheets
